US00D954467S

(12) **United States Design Patent** (10) **Patent No.:** **US D954,467 S**
(45) **Date of Patent:** **** Jun. 14, 2022**

(54) **SIDE CHANNEL**

(71) Applicant: **Edwin Chiquin**, Miami, FL (US)

(72) Inventor: **Edwin Chiquin**, Miami, FL (US)

(73) Assignee: **VERTILUX LIMITED**, Medley, FL (US)

(**) Term: **15 Years**

(21) Appl. No.: **29/710,244**

(22) Filed: **Oct. 22, 2019**

(51) LOC (13) Cl. **06-10**

(52) U.S. Cl.

USPC **D6/580**; D25/123

(58) **Field of Classification Search**

USPC D6/575-581; D25/119-125, 164; D26/138

CPC ... A47H 1/04; A47H 1/06; A47H 1/10; A47H 1/12; A47H 1/122; A47H 1/124; A47H 1/14; A47H 1/142; A47H 1/144; A47H 2001/047; E06B 2009/587; E06B 9/24; E06B 9/58

(57) **CLAIM**

The ornamental design for a side channel, as shown and described.

DESCRIPTION

FIG. 1 is a front perspective view of a side channel showing my new design;

FIG. 2 is a right side view thereof;

FIG. 3 is a rear view thereof;

FIG. 4 is a front view thereof;

FIG. 5 is a top view thereof;

FIG. 6 is a rear bottom perspective view thereof;

FIG. 7 is a left side view thereof;

FIG. 8 is a rear perspective view thereof;

FIG. 9 is a bottom view thereof; and,

FIG. 10 is a bottom rear perspective view.

The broken lines in the drawings represent environmental subject matter only and form no part of the claimed design.

1 Claim, 10 Drawing Sheets
